SPRAY GUN

John C. Hull, Gasport, N. Y., assignor to "Friend" Manufacturing Company, Gasport, N. Y., a Corporation of New York

Application July 15, 1930. Serial No. 468,189

1 Claim. (Cl. 299—116)

My invention relates to spray guns and more particularly has reference to an improved valve construction for spraying devices and its combination with the head of a spray gun.

- 5 It is an object of the present invention to provide a valve structure for spray devices which enables the graduation of a narrow long spray to any desired degree of width and which possesses maximum projective spraying power.
- 10 Another object of my invention resides in the provision of a spray gun which includes but a single moving part in the head or spray end thereof, the said moving part being simple in operation and inexpensive in construction.
- 15 Spray guns of present design are usually constructed of elements which require a high degree of precision thereby rendering the devices costly in manufacture. It is therefore still another object of the invention to provide a spray gun which 20 is characterized by its simplicity and freedom from complicated parts.

Other objects and advantages of my invention will appear from the more detailed description thereof.

- 25 Briefly stated, my improved construction comprises a hollow open-end tube, or valve-retaining member, having a plate or external flange at one end thereof, the plate preferably having angular openings in the rim thereof. Within the 30 tube and adapted for sliding movement therein is mounted a control and shut-off valve which, according to a specific embodiment of this invention, comprises an enlarged body portion of square cross section and a valve plug adapted for 35 insertion through and withdrawal from a central aperture in the plate or front end of the tube, this aperture preferably being of lesser diameter than the internal diameter of the tube. This structure is adapted for assembly into a spray 40 head of suitable construction, such as that shown in my prior Patents 1,221,861 granted April 10, 1917, and 1,561,646 granted November 17, 1925, and which includes a centrally apertured cap 45 threaded onto the head and a disc, having a spray orifice therein, which is held in position by the cap.

For a fuller understanding of my invention, reference will be had to the accompanying drawings illustrating a preferred construction but it 50 is to be understood that the invention is not limited to the specific showing as various changes and modifications may be made therein without departing from the spirit and scope of the invention as defined in the appended claims. In the 55 drawing,

Fig. 1 is a longitudinal sectional view of a spray gun embodying the features of my invention;

Fig. 2 is a view of the valve-retaining member or sleeve and its associated whirl plate; and Fig. 3 is a side view of Fig. 2.

60 Referring more particularly to the drawing, numeral 1 represents a conducting tube or barrel having screw threaded engagement at one end thereof with coupling 2, provided with inlet 3 which is threaded as at 4 for the reception of a 65 hose connection. A valve rod or shaft 5 is disposed centrally of the conducting tube and coupling, the latter having packing gland 6 and nut 7 for the shaft. The valve rod or shaft is provided with a screw or coarse thread 8, engaging 70 a corresponding helical recess within coupling 2, whereby the shaft may be moved longitudinally of the barrel with but a turn of the wrist, the outer end of the shaft having an enlarged actuating member 9 or handle for imparting rotation 75 to the shaft by the operator.

Screw threaded to the opposite or spray end of conducting tube 1, as shown, is a spray head or nozzle body 10 having a pressure chamber 11 formed therein. The outer end of the spray head 80 is threaded to receive a nozzle cap 12 having circular flange 13. A nozzle disc 14, having central spray orifice 15, and a gasket or washer 16 are disposed within cap 12 so that, when the latter is threaded into place on spray head 10, the gasket 85 16 is bound against the end of the spray head and disc 14 is bound between the gasket and flange 13 of the cap.

As a feature of the present invention, the outer 90 end of spray head 10 is bored, as shown, to receive a whirl plate 17 or external flange of the valve-retaining member hereinafter described, the outer rim of which plate or flange is milled to provide feed apertures 18. The plate forms an eddy chamber 19 with disc 14, the plate being 95 flush with the outer end of the spray head. The feed apertures are preferably four in number and equally spaced circumferentially of the plate and are cut at an angle to the plate, as best shown in Fig. 3, in order to impart a swirling motion to the 100 material passed therethrough.

A hollow cylindrical tube or sleeve extension 20 constitutes the valve-retaining member and extends backwardly from plate 17 into the head of the gun as shown, the tube and plate preferably being integral. Plate 17 is centrally apertured to provide a circular opening 21. The diameter of this opening is uniform to but a short distance from the face of the plate and increases in the direction of the interior of sleeve 20, as 110

shown, to form an internal flange 21'. In a preferred construction, the diameter of aperture 21 across the face of plate 17 is about one-half inch and this diameter extends not more than one-sixteenth inch into the plate. The diameter of aperture 21 then increases to merge, as shown, with the interior of sleeve 20 which is preferably bored to eleven-sixteenth inch. That is, the smallest thickness of flange 21' is not more than one-sixteenth inch which gradually increases to about eleven-sixteenth inch in the direction of the tube.

The tube or sleeve extension 20 of the whirl plate is adapted to slidably retain the control and shut-off valve which comprises the valve body 22 substantially square in cross section and the integral cylindrical valve plug 23. When the sleeve 20 is bored to eleven-sixteenth inch as above stated, valve body 22 is preferably about one-half inch square in cross section while valve plug 23 is lathed to fit the small diameter of aperture 21, its end being slightly tapered as shown. The outer end of plug 23 is provided with a resilient tip 24 of rubber or the like which is adapted to seat against orifice 15 to effect a shut-off, the valve plug being of sufficient length to permit this when the control valve is moved outwardly toward disc 14. Valve body 22 is bored to receive the end of valve rod or shaft 5 and is rigidly held thereon by means of cross pin 25.

In operation, the solution or mixture to be sprayed is supplied under pressure to the gun through inlet 3 and passes into pressure chamber 11 and into the spaces between the flat sides 35 of valve body 22 and the interior of sleeve 20. By moving the control valve backward and forward by rotation of shaft 5, the aperture 21 may be opened and closed at will, thus optionally effecting any desired degree of central discharge 40 through the head of the gun for the purpose of greater projective power of spray and making it possible to graduate a narrow long spray to any desired width. When the control valve is moved forward so that plug 23 is positioned in opening 45 21 but short of disc 14 as shown in Fig. 1, the

flow through the opening 21 is shut off and all the material issues in a whirling motion from pressure chamber 11 through feed apertures 18 into eddy chamber 19 and thence through orifice 15. When the valve is moved backwardly of the gun so that plug 23 is withdrawn from aperture 21, part of the material discharges through feeder apertures 18 and part through central opening 21 into eddy chamber 19 thereby effecting central discharge of a portion of the material and furnishing greater projective spraying power. In the movement of the control valve longitudinally of sleeve 20, it will be noted that the square corners of body portion 22 serve as a guide for the valve. In order to shut off the spray, the valve is moved outwardly to abut against disc 14 and close off orifice 15 by means of the resilient tip 24 on the valve plug.

From the foregoing it will be seen that I have devised an improved valve structure for spray guns for effecting a controlled central discharge and which is characterized by its simplicity of construction and minimum of moving parts.

Having described my invention, I claim:

A spray gun comprising in combination a spray head, a flanged nozzle cap secured to the head, a centrally apertured disc within the cap, a whirl plate fixed in the head in spaced relationship with the disc and having spaced tangential openings in the periphery thereof, a central circular opening in said plate in alignment with and of larger diameter than the aperture of said disc, a hollow cylindrical sleeve rigid with and extending from said plate, between the circular and tangential openings thereof backwardly into the spray head and spaced from the walls of the latter, a control valve slidably disposed in said sleeve comprising an enlarged body portion having spaced guiding contact with the sleeve and a cylindrical plug adapted to fit said circular opening and of sufficient length to reach from said opening to said disc, means for moving said valve lengthwise of the sleeve, and means for supplying liquid to said head.
